UNITED STATES PATENT OFFICE.

EDWARD K. WARREN, OF THREE OAKS, MICHIGAN, ASSIGNOR TO WARREN
FEATHERBONE COMPANY, OF THREE OAKS, MICHIGAN.

CORSET-STIFFENER.

No. 834,423.

Specification of Letters Patent.

Patented Oct. 30, 1906.

Application filed January 17, 1903. Serial No. 139,471.

To all whom it may concern:

Be it known that I, EDWARD K. WARREN, a citizen of the United States, residing at the village of Three Oaks, in the county of Berrien and State of Michigan, have invented 5 certain new and useful Improvements in Corset-Stiffeners, of which the following is a specification.

This invention relates to improvements in 10 corset-stiffeners adapted for use as dress-stays.

The object of this invention is to provide 15 an effective stiffener of proper size for such use at very small cost. For many uses, and also for cheap goods, great resiliency is not required, and consequently fibers and materials of low quality have usually been employed for these purposes. Also it is frequently desirable to use a stiffener which 20 while it is elastic and durable is not harsh.

It is the object of this invention to meet 25 these wants by providing a corset-stiffener of any required elasticity and strength at a moderate cost, although made of superior materials.

The material which I have invented and introduced on the market called "featherbone" is made up of fibered quills of feathers suitably bound together and is probably the 30 strongest and stiffest corset-stiffener known. I accomplish my results by utilizing this material in connection with non-resilient materials suitably assembled together.

The objects of this invention relating to 35 the details of construction will readily appear from the detailed description to follow.

I accomplish the objects of my invention by the devices and means described in the following specification. The invention is 40 clearly defined and pointed out in the claims.

A structure embodying the features of my invention is fully illustrated in the accompanying drawings, forming a part of this specification, in which—

45 Figure 1 is a detail view of a piece of corset-stiffener about full size embodying my invention. Fig. 2 is an enlarged detail view of the same, showing the undone strands spread out, so that their structure can be 50 readily understood. Fig. 3 is a detail cross-sectional view showing the arrangement of the parts.

In the drawings similar letters of reference

refer to similar parts throughout the several views.

55

Referring to the lettered parts of the drawings, my improved corset-stiffener is made up of a plurality of strands. The central strands A A consist of stiff cords made up of fibered quills suitably wound and bound together, as clearly appears in Fig. 2.

Adjacent to these strands and outside of the same I put strands of textile cord B B, preferably of the same size as the resilient stiffener to add breadth to the same. When the

60

four strands are thus arranged side by side, I wrap them with a single wrapping-thread C and immediately before the cords can be 65 come disarranged secure the same by a row of stitches D down the center, thereby mak-

70

ing up a flat cord four strands wide and one thick. The two central stiff strands coming close together make a very resilient backbone to the cord, while its edges are sufficiently extended by the textile cord to give the de- 75 sized size, and they serve somewhat to deaden the resiliency of the blade, making it, in effect, a cheaper blade. It is obvious that the

75

textile strands B B are inexpensive and that by adopting this method a blade of the resiliency of the ordinary cheap stiffener is secured at a greatly-reduced price. It is, in fact, made of superior and clean materials which are much more durable than strips of ratan or woody fiber that have hitherto 85 been used for the production of cheap stays.

80

It will also be noticed that these parts are secured together by a minimum amount of wrapping material, thereby lessening the expense of manufacturing. This small amount 90

90

of wrapping material is entirely sufficient, however, to properly secure this blade together, because the harsher stiff fibers do not come in contact with the wrapping-threads to offer great resistance to them. However, 95 the principal saving in the expense is in the elimination of the expense of featherbone cords, and there would be a great saving in expense if the parts were wrapped and secured together in the ordinary way.

100

Having thus described my invention, what I claim as new, and desire to secure by Letters Patent, is—

1. In a corset-stiffener, the combination of a central set of strands A A made up of fibered 105 quills bound together; textile cords B B at

each side of the same, a single wrapping-thread embracing the said strands, with a row of stitches down the center, thereby forming a flat blade, as specified.

- 5 2. In a corset-stiffener, the combination of a central set of strands made up of resilient fibers; textile cords at each side of the same, a single wrapping-thread embracing the said strands, with a row of stitches down the center, thereby forming a flat blade, as specified.
3. In a corset-stiffener, the combination of a central set of strands made up of resilient

fibers bound together; and lateral textile cords or strands arranged at each side thereof, and the whole suitably retained together to form a flat blade, as specified.

In witness whereof I have hereunto set my hand and seal in the presence of two witnesses.

EDWARD K. WARREN. [L. s.]
